UNITED STATES PATENT OFFICE.

LESTER P. WINCHENBAUGH, OF HYDE PARK, AND LAWRENCE GENTILE, OF MELROSE,
MASSACHUSETTS.

PROCESS OF MAKING COLORED PAPER.

1,384,290.

Specification of Letters Patent. Patented July 12, 1921.

Application filed December 28, 1920. Serial No. 433,619.

To all whom it may concern:

Be it known that we, LESTER P. WINCHENBAUGH and LAWRENCE GENTILE, citizens of the United States, residing at 220 Dana 5 Ave., Hyde Park, Massachusetts, and 9 Mt. Vernon Ave., Melrose, Massachusetts, have invented certain new and useful Improvements in Processes of Making Colored Paper, of which the following is a clear, full, 10 and exact description.

This invention relates to a process of making colored paper.

The principal object of the invention is to provide an improved process of making colored paper by which new and highly artistic designs and ornamental effects may be produced.

With the above object in view, the invention consists in a process involving the novel 20 features hereinafter described and particularly pointed out in the claims, the advantages of which will be readily understood and appreciated by those skilled in the art.

In the drawings, Figure 1 is a view in 25 sectional elevation of an apparatus which may be advantageously employed in carrying out the present process; and

Fig. 2 is an underside plan view of a portion of this apparatus.

30 In accordance with certain features of the present process, a finished paper which varies in thickness at different points is employed. The relatively thick and thin spots or areas in the paper may form a regular 35 design or have an irregular arrangement and such areas may be formed by watermarking the paper or may be due to an irregular, uneven or lumpy formation given to the paper in the process of manufacture 40 or they may be produced in any other suitable or convenient manner.

In coloring paper of this character, to 45 produce the desired ornamental effects, a coloring liquid which will penetrate or strike into the substance of the paper is employed and this coloring liquid is applied to one side of the paper in a regulated quantity sufficient to cause the same to strike completely through the paper at the thin 50 spots or areas therein but preferably so that it will not strike through the thick spots. This will give an ornamental effect on the side of the paper opposite that to which the coloring liquid is applied depending upon 55 the formation and arrangement of the thick

and thin spots. Ordinarily where the paper is watermarked, the design of the watermark will show distinctly on the latter side of the paper in the color which has been applied. Where the paper has an irregular 60 or lumpy formation above described, the latter side of the paper will have a cloudy, mottled or irregularly colored surface, the edges of the heavily colored areas gradually fading into the areas having little or no coloring, thus giving a very artistic effect. 65

The coloring liquid may be conveniently applied to the paper in the manner described by means of the apparatus illustrated in Figs. 1 and 2. This apparatus 70 comprises a container 2 for the coloring liquid consisting of a pipe provided with color delivery openings as indicated at 4 to which the coloring liquid is supplied in any suitable manner. To guide the paper 75 and hold the same in proper contact with the container, guide bars 6 arranged on opposite sides of the container are provided. The paper is passed alternately over the guide bars and under the container pipe so 80 that the pipe forms a bight or loop in the paper and the paper passes partially about the lower portion or face of the pipe where the delivery openings are formed. With this apparatus, as the paper is drawn past 85 the color delivery pipe 2, the coloring liquid may be deposited on the paper in quantity sufficient to cause the same to strike completely through the paper at least at the thin areas thereof. The coloring liquid 90 may be applied, however, in any other suitable way to produce the desired results. The coloring liquid may be applied over substantially the whole surface of the paper on one side thereof, or it may be applied 95 to certain localized areas according to the effect desired.

Where the coloring liquid is applied to the paper by means of a color delivery pipe as above described, the amount of the coloring liquid deposited on the paper may be 100 regulated by regulating the speed at which the paper is moved past the pipe, the greater the speed of the paper, the less the quantity of the coloring liquid deposited on the 105 paper.

The coloring liquid employed should be such that it will rapidly penetrate or strike into the paper and will dry quickly leaving substantially no deposit on the surface of 110

- 2
- paper. A solution of an anilin dye in alcohol, gasoline or similar solvent has been found in actual practice to give highly satisfactory results. When a dye solution of this character is used, the penetration of the dye may be regulated by adding a predetermined quantity of water to the solution, the addition of water reducing the penetration of the dye solution.
- 10 The quantity of the coloring liquid applied to the paper may be so regulated that the liquid will strike through the paper at all points. The thin areas, however, where the liquid strikes through to the greatest degree will then have the strongest coloring, while the color will be weaker or paler at the thick spots.
- Instead of a paper having relatively thick and thin areas, a paper which is of substantially the same thickness at all points, but in which certain areas will allow the coloring liquid to penetrate more readily than other areas as, for example, a paper in which the structure of the paper is denser at certain points than others, may be employed in the present process. When a paper of this character is used the coloring liquid is applied to one side of the paper in a regulated quantity so that it will strike through the paper at least at the areas which allow the liquid to penetrate most readily. The quantity of the coloring liquid applied to the paper may be so regulated that the liquid will strike through the paper at all points or that it will not strike through at the areas which allow the liquid to penetrate less readily. Thus, there will be produced upon the side of the paper opposite that to which the coloring liquid is applied, designs or ornamental effects similar to those produced when a paper varying in thickness at different points is employed.
- Having explained the nature and object of the invention, and having described the manner in which the invention may be applied, what is claimed is:
1. A process of making colored paper which comprises taking a paper which varies in thickness at different points therein and applying to one side thereof a penetrative coloring liquid in regulated quantity sufficient to cause the same to strike through the paper at least at the thin points therein.
2. A process of making colored paper which comprises taking a paper having a watermark therein and applying to one side thereof a penetrative coloring liquid in regulated quantity sufficient to cause the same to strike through the paper where the watermark is formed.
3. A process of making colored paper which comprises taking a penetrative coloring liquid and a paper certain areas of which will allow the coloring liquid to penetrate more readily than others, and applying the coloring liquid to one side of the paper in regulated quantity sufficient to cause the same to strike through the paper at least at the areas which will allow the liquid to penetrate most readily.

Signed at Boston, Mass., this 22nd day of December, 1920.

LESTER P. WINCHENBAUGH.
LAWRENCE GENTILE.
